INVENTOR

Ludwig K. Böhm.

UNITED STATES PATENT OFFICE.

LUDWIG K. BÖHM, OF NEW YORK, N. Y., ASSIGNOR TO THE ELECTRO GAS COMPANY, OF WEST VIRGINIA.

ACETYLENE-GAS GENERATOR.

SPECIFICATION forming part of Letters Patent No. 609,494, dated August 23, 1898.

Application filed June 1, 1896. Renewed May 25, 1898. Serial No. 681,755. (No model.)

To all whom it may concern:

Be it known that I, LUDWIG K. BÖHM, a subject of the Emperor of Germany, and a resident of New York city, in the county and State of New York, have invented certain new and useful Improvements in Automatic and Adjustable Acetylene-Gas Generators, of which the following is a specification.

This invention has reference to an acetylene-gas generator in which the pressure of the gas is regulated and adjusted by the height of the water-level in the reservoir which furnishes the water for the decomposition of the carbid.

It is further the object of this invention to provide a water-supply device, in combination with the gas-generating apparatus, which is relatively small and in which the height of the water-level can be varied at will, but remaining constant when adjusted to the desired height. Further, the water-reservoir itself may be raised or lowered, whereby the scale of raising or lowering the water-level is increased.

The invention is illustrated in the accompanying drawings, in which—

Figure 1 is a vertical section of the whole plant. Fig. 2 shows, mostly in section, the device for keeping the water-level constant at any desired height.

As is plainly seen from the drawings, the water from reservoir R descends through the water-supply pipe S and rises in cylinder B and upon reaching the carbid C in cylinder A decomposes the same, thereby generating the gas. When the pressure of the gas increases, then some of the water is forced back into reservoir R, thus stopping the generation of the gas; but when gas is used then the water rises again and produces more gas. Thus the gas is automatically generated and always in a quantity proportionate to the consumption.

The higher the level of the water in R and the higher R itself the greater will be the pressure of the gas, and the lower the water-level and the reservoir the more reduced is the pressure of the same. The gas leaves the generator through the gas-pipe P, which may connect directly with the piping which leads to the burners, or a gas-regulating valve or a

gas-reservoir may be interposed. The pressure of the gas is preferably increased during the hours of the largest consumption—that is, when practically all burners are lighted— 55 and is decreased during those hours when few lights are used.

The device D for varying the water-level in R and keeping it constant at any desired height is shown in Fig. 1 and in detail in Fig. 2. This device is a piston or plunger valve. It consists, essentially, of the piston a, the valve-casing, and the curved and graduated lever l, with weight. The lever-arm is supported by the fulcrum f, which is connected to the valve-casing by lever-arm b. The lever l carries the piston a by means of the sliding rod r. The water entering the piston-valve passes through the openings in the piston down into the lower portion of the valve-casing and leaves through the opposite end. If the pressure is greater in the water-supply pipe S², then the water flows through the piston into the tank R; but if the pressure in R becomes greater than in the water-supply pipe S² then the piston is forced up a little, so that the openings in the piston are no longer opposite to the opening o, thereby closing the piston-valve. As is plainly seen from this construction, the water-level in R can be 75 adjusted to any desired height by shifting the weight on the lever-arm l. If the weight is close to the piston-valve, the water-level is low; but if the weight is shifted farther away from the piston-valve then the water-level is maintained at a greater height. In this way any desired height of the water-level can be maintained by shifting the weight into the corresponding position on the lever-arm l. 90

In order to raise or lower the water-tank R, a device is provided, which is shown in Fig. 1. The water-supply pipe S consists of two parts, which slide in each other. The part s of the upper portion is inside of the enlarged top part s' of the lower portion of S. To the cylinder A is permanently attached by supporting bars a small cylinder F, into which extends s', and is permanently fixed into the bottom of F. The top portion of S, which is within the cylinder F, is enlarged in diameter, as shown in Fig. 1, and slides in

- F, being tightened at the top by a stuffing-box G. At the bottom of F a water-pipe S³ is provided, through which press-water is introduced when the tank R shall be lifted.
- 5 The press-water forces up R, carrying with it the device D by means of the sliding pipe s², which runs in the enlarged portion s³ of the water-supply pipe. By this arrangement is accomplished that the device D remains at
- 10 a constant distance from the water-level in tank R when the tank is raised.
- In the described manner an acetylene-gas plant is provided in which the gas is automatically generated as consumed and in which
- 15 the level of the water in the tank supplying the water for the decomposition of the carbide, and thereby generating the gas, may be varied at will for the purpose of increasing or decreasing the pressure of the gas.
- 20 The details of the construction may be varied without changing the nature of the invention.
- Having now described my invention, what I claim therein as new, and desire to secure
- 25 by Letters Patent, is—
1. An automatic and adjustable acetylene-gas plant consisting of a gas-generating apparatus in which the gas is automatically generated as consumed, a water-supply reservoir with water-supply tube which consists of two parts sliding in each other, for the purpose of raising or lowering the water-reservoir, substantially as described.
- 30 2. An automatic and adjustable acetylene-gas plant consisting of a gas-generating apparatus in which the gas is automatically generated as consumed, a water-supply reservoir with water-supply tube which consists of two parts sliding in each other for the purpose of raising or lowering the water-reservoir and a water-level regulator provided
- 35 with a sliding device so that the regulator remains always at a constant distance from the water-level in the reservoir when the same is raised or lowered, substantially as described. 45
3. An automatic and adjustable acetylene-gas plant consisting of a gas-generating apparatus, a water-reservoir whose supply-tube consists of two parts sliding in each other, a water-level regulator with sliding device, and a small cylinder between the reservoir and the gas-generator and permanently attached to the generator and provided with a supply-tube for introducing press-water in the cylinder for the purpose of raising and lowering the water-reservoir, substantially as described. 50
4. In an automatic and adjustable acetylene-gas plant a water-supply consisting of the reservoir proper which can be raised and lowered and whose water-level can be adjusted, a water-level regulator provided with a sliding device, and a water-supply pipe consisting of two parts which slide in each other, substantially as described. 55
5. In an automatic and adjustable acetylene-gas plant a water-supply consisting of the reservoir proper which can be raised and lowered and whose water-level can be adjusted, a water-level regulator provided with a sliding device, a water-supply pipe consisting of two parts which slide in each other and a small cylinder surrounding the top portion of the water-supply pipe with a pipe through which press-water is introduced, substantially as described. 60
- 65
- In testimony whereof I have hereunto set my hand in the presence of two subscribing witnesses.
